UNITED STATES PATENT OFFICE

2,688,321

AUTOMATIC REPEATING GAS PISTOL

Robert S. Martin, Los Angeles, Calif.

Application September 14, 1950, Serial No. 184,731

2 Claims. (Cl. 124—11)

1

This invention relates to fluid pressure operated guns, particularly pistols and rifles, which operate on the air or gas storage and release principle, but the invention is not limited to these devices.

Air pistols and rifles use a pumping mechanism to store air under pressure within a chamber where it is released by the striking action of a hammer upon a valve, causing the latter to open and release the compressed air or gas into the barrel behind a projectile, as a pellet or ball, ejecting the latter with varying decrease of force and velocity. Gas pistols and/or rifles employ similar principles of storage without, however, the necessity of pumping or compression since the gas is already available in compressed condition under pressure either in small bulbs, such as the conventional Sparklet or Soda King CO₂ bulb, or in larger cylinders of carbon dioxide which, by means of a check valve or other suitable mechanism, is introduced into a long cylinder attached to the pistol or rifle in the form of a secondary barrel; the principle of release of the said gas into the actual rifle or pistol barrel to eject the projectile therein is substantially the same.

Another method for the storage and release of gas where the gas is in a bulb container is to insert the said bulb into the grip or butt of the pistol, sealing the same therein and piercing the bulb in such a manner as to meter the gas into a storage chamber which surrounds the pistol or rifle barrel; then by means of a tripping effect a sleeve which surrounds the rifle or pistol barrel is forced back, exposing openings in the rifle or pistol barrel through which the stored gas escapes and expels the projectile seated in the rifled barrel. Upon the expulsion of the gas from the above described storage chamber, the sleeve is reset by means of a reset button, a lever is pulled back again, metering gas from the bulb into the storage chamber and so on.

The foregoing methods for the storage and release of gas or air in the said air or gas rifles and pistols are awkward and have certain drawbacks; for example, the pumping of air or the release of air or gas into a storage chamber where the said medium must then be released by means of a hammer striking a valve produces a hard trigger pull and destroys precision in shooting, the force necessary to open the valve being great. In addition, the valves have a tendency to leak. Where gas is metered from a bulb into a storage chamber, the operation is slow, and the user is limited to a single shot, after which a number of operations must take place before another shot is possible.

2

An important object of the invention is to provide an air or gas pistol and rifle, which is constructed and arranged to overcome the disadvantage of the conventional air or gas pistols and rifles as above described.

Another object is to provide an air or gas pistol or rifle which eliminates the need for metering air or gas into the storage chamber thereof.

Another object is to provide an air pistol or rifle including means for automatically refilling the storage chamber thereof, so that the operation of the pistol or rifle may be continued without resetting or metering until the gas in the bulb supplying the storage chamber is exhausted.

15 Another object is to provide an air pistol or rifle in which is eliminated the need for a hammer or like device for opening a valve to allow the air or gas to escape into the barrel for the purpose of propelling a projectile.

20 Another object of my invention is to provide an air pistol or rifle in which the rate of flow of the gas, from the storage chamber into the pistol or rifle barrel, is increased, thus cutting down the time lag as well as increasing the actual pressure of the gas itself upon the projectile.

25 Other objects and advantages will appear hereinafter as this specification progresses.

The invention is illustrated in the annexed drawings, which form a part of this specification, and in which:

Fig. 1 is a side elevation of an air or gas pistol embodying my invention, showing the pistol in cocked position for shooting the same.

Fig. 2 is a longitudinal section of my pistol as shown in Fig. 1, with the pistol shown loaded and cocked for shooting same.

Fig. 3 is a longitudinal section of my air or gas pistol, showing the position of the parts after the pistol has been shot.

40 Fig. 4 is a fragmentary longitudinal section, on an enlarged scale, of the loading means of my pistol, shown in its cocked position, as shown in Fig. 2.

Fig. 5 is a fragmentary longitudinal section, on an enlarged scale of the loading means of my pistol, shown in its position after being shot, as shown in Fig. 3.

45 Fig. 6 is a fragmentary longitudinal section of a modification of my invention, on an enlarged scale, showing the same in cocked position before the trigger is pulled to project a bullet.

50 Fig. 7 is a view like Fig. 6, but showing the trigger pulled and the parts brought into position for projecting a bullet.

55 Fig. 8 is a transverse vertical section of my invention taken on line 8—8 of Fig. 7.

Fig. 9 is a transverse vertical section of my invention taken on line 9—9 of Fig. 7.

Fig. 10 is a transverse vertical section of my invention taken on line 10—10 of Fig. 7.

Fig. 11 is a transverse vertical section of my invention taken on line 11—11 of Fig. 7.

Referring more particularly to the drawings, in which the same parts are designated by the same reference numerals in all of the views, my invention, as illustrated in Figs. 1, 2 and 3 in the form of a pistol, includes generally a breech 1; a barrel 2 extending forwardly from said breech; a handle 3 depending rearwardly at an angle from said breech; a conventional air or gas storage bulb 4 detachably retained within said handle; an elongated barrel tube 5 slidably mounted in said barrel 2 and extending from within the rear part of the breech 1 through said barrel 2; a loading means 6 for loading a tube 7 containing pellets 8 in the rear part of said barrel tube 5; a trigger mechanism 9 for controlling projection of said bullets 8 from said loading tube 7; and spring seal actuating means 10 controlled by said trigger mechanism for admitting air from said air or gas storage bulb 4 into said barrel tube 5 behind the foremost pellet 8 in said loading tube 7 in said loading means 6 in the rear end of said barrel tube for projecting said pellet from the forward end of a loading tube 7 through said barrel tube, when said trigger mechanism is actuated by pulling its trigger 11.

The loading means 6 comprises the rear end portion 12 of the barrel tube 5, which portion of said tube receives the cartridge 7 containing bullets 8; a cap 13 threaded at 14 on the rear end of said rear end portion 12 of said barrel tube 5, which cap engages the rear end of said cartridge 7 for positioning said cartridge properly in loaded position in said rear end portion 12 of the barrel projection tube 5, in which rear end portion 12 of said tube are located a plurality of air or gas ports 15 at the rear of the first pellet 8 in the forward end of said cartridge 7; a ring gasket 16 slidably fitted on said barrel tube 5 and closing said ports 15 when said tube 5 is in retracted position; a trigger mechanism sear 17 secured on said rear end portion of the barrel projection tube 5, which sear is engaged by an engaging arm 18 on the forward end of a barrel tube arresting lever 19 of the trigger mechanism 9, for holding the barrel projection tube 5 in its retracted and cocked position; and a coil spring 20 surrounding said rear end portion 12 of the barrel tube 5 between said sear 17 and a shoulder wall 20' of the breech 1, against which spring 20 is compressed when the barrel tube 5 is retracted and the pistol is cocked.

In the forward end portion of the breech 1 and at the rear end of the barrel 2 is formed a cylindrical bore 21 extending coaxially with said barrel, through which bore coaxially extends the barrel tube 5, and in the rear end of which bore is fitted the ring gasket 16, through which gasket said tube 5 slidably extends, there being a plunger 22 slidably fitted in said bore 21 and a coil spring 23 surrounding the barrel tube 5 in said bore between said plunger and the forward end of said bore, and there being a stop 24 in the form of a collar or C ring secured on said barrel tube 5 between said plunger 22 and the ring gasket 16, in an air and gas chamber 25, formed by said bore, between said plunger 22 and the ring gasket 16 in the rear end of said bore.

In the pistol handle 3 and lower part of the breech 1 is formed a pocket 26 for the air or gas

bulb 4, which pocket is closed at its upper end by a breech wall 27 and is open at its lower end, but said lower end of said pocket is normally closed by a screw plug 28, which is threaded in said pocket lower end, as indicated at 29, for detachably holding the air or gas bulb 4 in said pocket 26. A small bleed tube 30 extends from the air and gas chamber 25 through a portion of the breech 1 into the upper end of the bulb pocket 26, and the lower end of said tube 30, in said upper end of said pocket, is tapered and pointed as shown at 31, so that when an air or gas bulb 4 is introduced into said pocket 26 through its lower end, and the plug 28 is screwed into said lower end of said pocket against the lower end wall of said bulb 4, said bulb will be forced upwardly in said pocket by said plug 28 and said lower pointed end 31 of said tube 30 will puncture the upper end wall of the air and gas bulb 4 and project into the upper end of said bulb, whereupon the air or gas under pressure in said bulb 4 will bleed from said bulb out through said tube 30 into the air or gas chamber 25, where said air or gas, acting upon the plunger 22, will maintain said plunger in its forward position against the tension of the spring 23, as shown in Fig. 2 of the drawings.

The ring gasket 16 in the air and gas chamber 25, and the ports 15 in the slideable barrel tube 5 which slides through said gasket, form a seal 32 for controlling the admission of air or gas under pressure from the air or gas chamber 25 into the barrel tube 5 and into a loading tube 7 in the rear end portion of said barrel tube, behind the foremost pellet 8 in said loading tube for projecting said pellet from the pistol through the barrel tube 5.

The spring seal actuating means 10, which is controlled by the trigger mechanism 9, for actuating the seal 32, comprises the slideable barrel tube 5; the sear 17 secured on said barrel tube for engagement by the arm 18 of the barrel tube arresting lever 19 of the trigger mechanism 9, for arresting said tube in its retracted position and the seal 10 in its closed position; and the coil spring 20 surrounding the rear end portion 12 of the barrel tube 5 for compression between the sear 17 and the shoulder wall 20', when the barrel tube 5 is retracted and the pistol is held cocked by the engagement of the sear 17 by the arresting lever 19.

The trigger mechanism 9 includes the trigger 11, which is pivoted on a pivot pin 33 mounted in the forward end of a trigger frame 34 forwardly of the breech 1 and below the barrel 2; the barrel tube arresting lever 19, pivoted at 35 in the breech 1, and formed with a depending rounded abutment 36 on its rear end; a bell crank trip lever 37, formed with a long horizontal arm 38 and a short vertical arm 39 extending upwardly from the forward end of said long arm, and a rounded head 40 extending upwardly from the rear end of said long arm adjacent the abutment 36 on the rear end of said barrel tube arresting lever 19, the trip lever 37 being pivoted at the juncture of its arms 38 and 39 in the breech 1 by a pivot 41; a connecting rod 42, connected at its forward end to a short arm 43 extending upwardly from the upper pivoted end of the trigger 11, and connected at its rear end to the short vertical arm 39 of the trip lever 37; and a coil spring 44 surrounding said connecting rod 42, bearing at its rear end against said short vertical arm 39 of the bell crank trip lever 37, and bearing at its forward end against a bear-

ing 45 in the breech 4, through which bearing said connecting rod 42 freely extends.

The loading tube 7 used in my pistol and rifle comprises a cylindrical shell 46 closed at its rear end by an end wall 47 and open at its forward end and formed with a plurality of inwardly converging spring fingers 48 and provided with a plurality of air or gas inlets 49 in the shell 46 near the forward end thereof, adapted to register with a plurality of air or gas inlets 15 in the barrel tube 5 to admit air or gas from the chamber 25 into the shell 46. The pellets 8 are each formed with a spherical head 50 and a conical skirt 51 at the rear of said head. The pellets 8 fit closely in the shell 46 and are placed longitudinally in the shell with their spherical heads 50 forward and their skirts 51 rearward. A coil spring 52 is placed in the rear part of the shell 46, bearing at its rear end against the rear end wall 47 of the loading tube 7 and the forward end of said spring bearing against the skirt 51 of the rearmost pellet 8 in said shell and forcing all of the pellets, one against the other forwardly in said shell until arrested by the engagement of the spherical head 50 of the foremost pellet in the shell with the inner sides of the spring fingers 48 on the forward end of the shell 46.

The operation of my invention is as follows:

The bulb 4 being filled with highly compressed air or gas and held in the pocket 26 in the handle 3 and breech 4 of the pistol by the screw plug 28, with the pointed lower end 31 of the needle tube 30 having punctured the upper end wall of the air or gas bulb 4 and extending into the upper end of said bulb, so that the air or gas bleeds from said container through said needle tube 30 into the chamber 25, the pistol may be first set for projecting a pellet 8 by drawing the barrel tube 5 rearwardly against the tension of the spring 20 until the arm 18 of the barrel-tube arresting lever 19 of the trigger mechanism 9 engages the forward side of the barrel-tube sear 17 and arrests said barrel tube 5 in its retracted position; the pistol is then loaded by placing a loading tube 7 containing pellets 8 in the loading means 6, upon unscrewing and removing the cap 13 from the rear end of the barrel tube 5 and introducing said loading tube into the rear end portion 12 of said barrel tube and then screwing the cap 13 on the rear end of the barrel tube 5 until said cap, engaging the rear end wall 47 of the loading tube 7, forces said loading tube forwardly into said barrel tube until the air or gas inlets 49, in the forward end portion of said loading tube, register with the air and gas inlets 15 in the barrel tube 5; upon pulling the trigger 11 the barrel-tube arresting lever 19 is swung clockwise on its pivot 35, through the medium of the trigger arm 43, connecting rod 42, and trip lever 37, against the tension of the spring 44, until the sear engaging arm 18 of said arresting lever 19 disengages the forward side of the sear 17, so that the spring 20, engaging the sear 17, forces the barrel tube 5 forwardly in the barrel 2 until the inlets 15 in said barrel tube pass beyond the ring gasket 16 and break the seal 32, whereupon the air or gas under high pressure in the chamber 25 passes through said inlets 15 into the forward end portion of the loading tube 7, behind the foremost pellet 8 in said loading tube, and said pellet is projected by said air or gas forwardly past the spring fingers 48 on the forward end of said loading tube 7 and out through the barrel tube 5 and barrel 2, said spring fingers 48 thereupon springing back inwardly to arrest the next

following pellet 8 projected forwardly in the loading tube 7 by the coil spring 52 in the rear end portion of said loading tube 7; as the compressed air or gas passes out of the chamber 25 through the ports 15 in the barrel tube 5 and through the inlets 49 into the loading tube 7, and thence out through the barrel tube 5 behind said foremost pellet 8, the air or gas pressure in said chamber 25 is relieved at the rear of the plunger 22 and said plunger is forced rearwardly by the expansion spring 23 against the stop 24, secured on the barrel tube 5, whereupon said plunger, engaging said stop, forces said stop and the barrel tube 5 rearwardly until the sear 17 on said barrel tube passes over the sear engaging arm 18 of the barrel tube arresting lever 19, depressing said sear and the sear end of said arresting lever, until said sear 17 escapes said sear engaging arm 18, whereupon said arresting lever 19 swings counterclockwise by gravity, until the arm 18 on the forward end of said arresting lever 19 engages the forward end of said sear 17 and arrests the barrel tube 5 in its retracted position and cocks the pistol for a repetition of the above described cycle of operations and particularly the projection of the next foremost pellet 8 in the loading tube 7 from the forward end of said loading tube and out through the barrel tube 5 as above described. Each time a pellet 8 is projected by the pistol and the pistol is returned to its cocked position, with the sear engaging arm 18 of arresting lever 19 engaging the sear 17 and holding the barrel tube 5 in its retracted position and the air or gas inlets closed by the ring gasket 16 of the seal 32, the air or gas continuing to bleed from the bulb 4 through needle tube 30 into the chamber 25, builds up sufficient pressure in said chamber to force the plunger 22 back to its initial position against the tension of the spring 23 until the spring is compressed sufficiently to force the plunger 22 rearwardly against the abutment 24 to cock the pistol with its barrel tube 5 in its retracted position for projecting the next pellet from the pistol when the trigger 11 is pulled the next time.

The operation of my invention, as above described, applies to a semi-automatic gun, in that it is assumed that the trigger is released each time a pellet is projected from the gun and the gun is cocked by the spring 23, after projecting each pellet, for projecting the succeeding pellet.

Upon pulling the trigger and holding it without releasing it, the engaging arm 18 will not engage the sear 17 to hold the gun cocked, whereupon the projecting operation of the gun, as above described, will be repeated until all of the pellets in the loading tube 7 will be successively projected therefrom. My gun operated in this manner without releasing the trigger then becomes an automatic gun.

It will be obvious that my gun may be operated as a semi-automatic gun or as a full automatic gun, depending upon whether the trigger is released after projecting a pellet.

The modification of my invention shown in Figs. 4 to 9, inclusive, is substantially the same in construction as the form of my invention shown in Figs. 1 to 3, inclusive, of the drawings, except that a stationary barrel tube 5' is secured in the barrel 2 and is substituted for the slideable barrel tube 5 and a slideable sleeve 55 is fitted on said stationary barrel tube 5', the rear end portion of which sleeve extends rearwardly through and beyond the rear end wall 56 of the air or gas chamber 25, and said sleeve 55 carries, on its rear outer end, the sear 17 and, interme-

diate its ends, in the chamber 25, the abutment 24, while the plunger 22 is slidably fitted on said sleeve 55 in the bore 21 and is engaged by the spring 23, and said sleeve 55 is provided with inlet ports 57 arranged to register with the inlet ports 15' in the barrel tube 5' when the sleeve 55 is projected forwardly by spring 20, which ports 15' register with the inlet ports 49 in the loading tube 7 in loading position, in the rear end portion 12' of the barrel tube 5'.

I claim:

1. A fluid-pressure operated automatic gun including a loading means for a loading tube containing pellets, a fluid storage chamber, a fluid supply bulb, means for bleeding fluid from said bulb into said storage chamber, a seal for sealing off fluid from said storage chamber to the rear of the foremost pellet in said loading tube, a trigger mechanism for holding said seal in sealing position when the gun is cocked, a spring for opening said seal upon pulling the trigger of said trigger mechanism for admitting fluid under pressure behind said foremost pellet for projecting said pellet from the gun, said loading tube containing means for advancing the next pellet in said tube into projecting position, when the foremost pellet is projected from said loading tube and the pistol, a plunger forming one end of said storage chamber, a spring engaging said plunger, which plunger is moved against said plunger engaging spring to enlarge said chamber and compress said plunger engaging spring, when the gun is cocked and said seal is closed and pressure is built up in said chamber, and means engaged by said plunger under pressure of said plunger spring for cocking the gun.

20

15

25

30

35

2. A fluid-pressure operated automatic gun including a detachable fluid supply bulb, a loading tube for containing a plurality of pellets, a seal for sealing off said fluid from said pellets when the gun is cocked, a trigger mechanism for holding the gun cocked, said seal being arranged to be opened when the trigger of said trigger mechanism is pulled, to permit said fluid from said bulb to project the foremost pellet from said loading means of the pistol, means for bringing the next pellet into projecting position each time a pellet is projected as aforesaid, a plunger, a plunger engaging spring, which plunger is moved forwardly by said fluid against the tension of said spring to compress said spring when the seal is closed, and means engaged by said plunger under the influence of said plunger spring for cocking the gun, when said seal is opened, upon pulling the trigger of said trigger mechanism.
